UNITED STATES PATENT OFFICE.

ALBERT L. MUREN, OF DETROIT, MICHIGAN.

FLAME SIGHT FOR STEAM AUTOMOBILES.

Application filed October 20, 1924. Serial No. 744,748.

The invention relates to a construction for rendering the flame of a steam generator visible from the driver's seat of an automobile.

5 The primary object of the invention is to provide a simple arrangement whereby the flame is directly visible by the operator of the car without the necessity of employing reflectors or other indirect means. Another object is to provide a construction having a straight conduit extending from the driver's compartment to the point adjacent the pilot light so that both the main burner and the light may be observed. A still further 15 object is to arrange a spark plug or other ignition means for the pilot burner so that it also may be observed through the conduit.

These and other objects are attained by 20 the novel construction hereinafter fully described and illustrated in the accompanying drawings wherein:—

Figure 1 is a side view partly in section of a steam boiler and the flame sight shown 25 in relation to the driver's seat;

Figure 2 is a plan view of the boiler and observation tube, the former being broken away to disclose the pilot burner;

Figure 3 is a longitudinal section through 30 the pilot burner on the line 3—3 of Figure 2;

Figure 4 is a side view of a modified construction.

A is a steam generator located under the 35 hood of a steam driven automobile and provided with a burner B consisting of a perforated plate B' through which the fuel is delivered from the mixer C and the inlet conduit C'. D is a pilot burner fed through 40 a separate mixer D' by means of the inlet conduit D'', the latter being arranged to extend over the pilot burner so that the fuel will at all times be preheated when the burner is in operation. As shown, this pilot 45 burner consists of a radially extending casting E having a series of parallel slots E' through which the mixture is delivered.

F is a spark plug inserted in the burner casing adjacent the pilot burner D, the plug being provided with an electrode G extending 50 closely adjacent the side of the casting E to form a spark gap H therebetween. I and I' are the terminals connected respectively to the electrode G and the pilot burner D, these terminals extending to a suitable 55 source of high tension current.

The driver's seat is represented by the letter J and has the floor boards J', inclined toe boards J'' and dash J''' forming the front compartment of the automobile. 60

In order that the operator of the vehicle may at all times be able to ascertain whether or not the burner is lighted there is provided a conduit K secured to the burner casing and extending upwardly therefrom at a suitable inclination so that the operator of the vehicle when in normal position will have a clear vision through said conduit and may observe the flame from the main burner and the pilot burner as well as being able 70 to see the spark from the spark plug. As shown in Figure 1, the conduit K extends upwardly through an aperture L in the toe board J'' and is provided at its upper end with a cap M having a transparent top M' 75 of glass or other suitable material.

In the modified construction as shown in Figure 4, the conduit N extends only a short distance from the burner casing and is provided with a cap N' having the transparent top piece N''. The toe board J'' is, however, provided with an aperture O in alignment with the longitudinal axis of the conduit N and preferably this aperture is closed by a 80 glass cap P or other suitable transparent 85 covering.

With the construction as above described, the operator may at all times directly observe the condition of the main burner and the pilot burner from the driver's seat without changing from the normal driving position. If for any reason, the main burner flares back during the operation of the vehicle and blows out the pilot burner as occasionally 90 happens with steam driven automobiles, the driver will be immediately aware of that fact and may relight the pilot burner by means of the spark plug F, a suitable switch Q being provided for that purpose. Since the spark plug is also in alignment with the 95 conduit K the driver will be able to observe the spark. 100

The arrangement as above described forms a very simple means for at all times determining the condition of the burner and by placing the transparent cap for the conduit at a sufficient distance from the frame there will be no danger of having it destroyed by the heat from the burner. This arrangement eliminates the use of any reflecting means 105 and enables the driver to directly observe the flame itself. 110

What I claim as my invention is:—

1. In a steam automobile, the combination with a steam generator and a burner therefor, of a conduit extending from said generator at an inclination to the same, the longitudinal axis of said conduit being aligned with the burner and with the driver's compartment whereby the operator of the automobile may directly observe the burner flame.
2. In a steam automobile, the combination with a burner casing and a burner thereon, of a straight conduit extending from said burner casing in a direction to align said burner with the eye of the automobile operator when said operator is in normal driving position.
3. In a steam automobile, the combination with the front seat compartment of an automobile provided with floor boards, of a steam generator arranged forward of said compartment, a burner in said generator, and a conduit extending from said burner towards said compartment in alignment with an aperture in said floor boards, the longitudinal axis of said conduit extending in a

direction to align said burner with the eye of the automobile driver when said driver is in normal driving position.

4. In a steam automobile, the combination of a steam generator, a main burner therefor, a pilot burner, a spark plug adjacent said pilot burner, a burner casing and a conduit attached to said burner casing and extending in a direction to permit direct observation therethrough from the driver's seat of said spark plug, said main burner and said pilot burner.

5. In a steam automobile, the combination of a steam generator, a main burner, a pilot burner, a spark plug having an electrode adjacent said pilot burner forming a spark gap therebetween, a burner casing, a conduit extending from said burner casing at a point adjacent said spark plug, and a transparent closure for said conduit, said conduit extending in a straight line towards said driver's seat to permit direct observation of said spark plug, pilot burner and main burner therethrough.

In testimony whereof I affix my signature.

ALBERT L. MUREN.
